Abel S. Clapp

United States Patent Office.

ABEL S. CLAPP, OF NEW YORK, N. Y.

Design No. 3,820, dated January 25, 1870.

DESIGN FOR CARRIAGE-BODIES.

The Schedule referred to in these Letters Patent and making part of the same.

I, ABEL S. CLAPP, of the city of New York, county and State of New York, have invented and produced a new and original Design of Conformation of Carriage-Bodies, of which the following is a specification.

The nature of my design is fully illustrated in the accompanying drawings.

Figure 1 is a side view,

Figure 2, a horizontal plan view, and

Figure 3, a hind end view of the carriage, without the running-gear, in which there is nothing particularly new.

It will be seen that there are two distinct compartments in the carriage, A and B, the seats being transverse in A, and lengthwise in B, and that there is an

entrance on either side in A, and a hind entrance to B, and that one top covers both compartments.

The elevated driver's seat C has its own distinct canopy.

A continuous dash-board, I, over the wheels, is affixed to each side, so shaped as to form the steps at the entrance, on each side of the front compartment A.

Claim.

I claim, as my invention—

The design of the carriage-body, as shown.

Witnesses:

ABEL S. CLAPP.
